UNITED STATES PATENT OFFICE

WILLARD E. ERICKSON, OF CHICAGO, ILLINOIS, ASSIGNOR TO LINK-BELT COMPANY, OF CHICAGO, ILLINOIS, A CORPORATION OF ILLINOIS

EXTERNAL COUNTERWEIGHT DEVICE FOR GONDOLA CAR DUMPERS

Application filed December 19, 1927. Serial No. 240,994.

My invention relates to improvements in car dumpers and has for one object to provide a new and improved type of car dumper wherein the car is held in place on the cradle by a car holding clamp, the clamp being held in place by a counterweight, which counterweight is supported at a point removed from the cradle. Another object is to provide means whereby greatly increased clamping effect may be obtained and whereby a relatively light clamp counterweight may be used. Another object is to provide a car dumper wherein the clamps are held in place through the differential action of a counterweight control drum. Other objects will appear from time to time throughout the specification and claims.

My invention is illustrated more or less diagrammatically in the accompanying drawings, wherein:

Figure 1 is a diagrammatic end view with parts in section with the car in the upright position;

Figure 2 is a view similar to Figure 1 with the car tilted to the point where the clamps engage the car;

Figure 3 is a similar view showing the car in a still further tilted position;

Figure 4 shows the car in the final extreme dumping position;

Figure 5 is an elevation in part section of the holding drum;

Figure 6 is a section along the line 6-6 of Figure 5;

Figure 7 is a side elevation of the cradle with parts in section.

Like parts are indicated by like characters throughout the specification and claims.

The cradle comprises two or more roller rings A, traveling and supported by fixed rollers A¹ A¹ on brackets A² A² on the foundation A³. The hopper A⁴ which is carried on the foundation is located beneath the cradle and adapted to receive the material discharged from the car when in the dumping position. A framework comprising built up girder sections indicated diagrammatically at A⁵ A⁶ A⁷ A¹⁷ joins the roller rings together and the entire assembly is rotated by means of a cable A⁸ dead ended at both ends

on the roller ring, wrapped around the ring and around a sheave A⁹, power being applied to the sheave through a driving shaft A¹⁰ from any suitable source of power to rotate the assembly.

Mounted on one side on the framework A⁵ is a buffer plate B adapted to engage the side of the car as the cradle rotates. The car itself rides on rails B¹ on the laterally movable transfer table B² which table is supported on rollers B³ on track plates B⁴, the idea being that as the cradle rotates from the upright position shown in Figure 1 toward the dumping position, the transfer table and car will move to the left until the side of the car engages the plate B, the movement being greater or less as the case may be depending upon the clearance between the car and the sides of the cradle. At some time after the transfer table has moved and come to rest and the car engages the plate B, the clamp carriage B⁵ will descend along the guide column B⁶ which is a part of the frame A⁶ until the car clamping shoe B⁷ on the clamp carriage engages the top of the car. Shortly before this the car engaging shoe B⁸ on the clamp beam B⁹ will also engage the top of the car, the beam B⁹ being pivoted on the carriage B⁵ to permit relative movement thereby compensating for any inaccuracy or irregularity in the height of the car. My invention relates to the means for raising and lowering the clamps and to the means for holding them in position to take the load of the car as the cradle is rotated to the dumping position.

Referring first to the means for raising and lowering or resetting the clamps, the cable C is dead ended at the upper end of the guide B⁶, extends over a sheave C¹ on the clamp carriage B⁵ thence up over a sheave C² on the guide member B⁶ and thence down to the small diameter clamp drum C³ about which it is wound, thence extends about a sheave C⁴ on the roller ring A across over a sheave C⁵ on the lifting carriage C⁶ and thence back to the point C⁷ where it is dead ended adjacent the sheave C⁴. The lifting carriage C⁶ is provided with rollers C⁸ C⁹ adapted to travel along the curved guides

C⁹ in the roller ring A so that the sheaves C⁴ and C⁵ may be permitted to move toward each other and may be drawn up by the cooperation of the stop C¹⁰ 5 on the foundation with the stop engaging lug C¹¹ on the lifting carriage. In the position shown in Figure 1 the sheaves C⁴ and C⁵ are drawn apart, thereby the drum C³ is rotated, raising the clamps away from the car. 10 D is the holding rope dead ended below the buffer plate B on the far side of the cradle. It extends up about the sheave D¹ on the clamp beam B⁹ thence across about a sheave D² on the clamp carriage B⁵ thence down 15 to where it is wound about a drum D³ rigidly connected to and rotating with the clamp drum C³ upon which drum it is dead ended. When in the position shown in Figure 1, this rope is paid out. When in the position shown 20 in Figure 2, this rope has been wound about the drum into the shortened position and the car is held in place on the cradle.

E is a counterweight drum concentric with the drum D³. Mounted on the clamp drum C³ is a ratchet E¹. A dog E² on the drum E is adapted to be yieldingly forced by the spring E³ into engagement with the ratchet to lock the two drums together. The tail of 25 the dog has a roller E⁴. When the parts are in the position shown in Figure 1 this roller is engaged by a cam E⁵ to hold the dog out of engagement with the ratchet and leave the two drums, namely the clamp drum and the counterweight drum free to rotate with respect to each other independently. Wound 30 about the counterweight drum and dead ended thereon is a cable E⁶ extending down over a sheave E⁷, thence over a sheave E⁸ on the take-up or clamp lifting counterweight E⁹ and thence up to the point E¹⁰ where it is dead ended. This cable tends to rotate the counterweight drum in a clockwise direction. It will be noted that as the cradle rotates from 35 the position shown in Figure 1 to the position shown in Figure 2, the distance between the drum and the sheave E⁷ decreases somewhat and the counterweight drum is rotated, allowing the dog to travel along the cam but it does not travel far enough to bring the 40 roller out of engagement with the cam and to permit the clamp and the counterweight drums to be locked together.

F is the clamp holding counterweight cable. It extends from the counterweight 45 F¹, up over the sheave F² and is wound about and dead ended on the counterweight drum, being wound about it in a direction opposite to the take-up cable. The take-up sheave tends to rotate the counterweight drum 50 against the tension of the counterweight cable and while the parts are in the position shown in Figure 2, the counterweight cable and the counterweight drum exert no influence whatever on the clamps. Further rotation of the cradle however into the position shown in 55

Figure 3 lengthens the counterweight cable between the sheave F² and the drum. Since this cable is balanced between the holding counterweight and the take-up counterweight, this causes rotation of the counterweight drum into the position shown in Figure 3. When the roller on the tail of the dog leaves the cam, the spring engages the ratchet and the clamp and counterweight drums are 60 locked together. Further rotation of the cradle causes the counterweight cable to be drawn out over the sheave F² and moves the counterweight from the position shown in Figure 3 to the position shown in Figure 4. At this time the counterweight carries a turning movement on the counterweight drum and the clamp drum and thereby the weight of the counterweight is effective to hold the clamp in place to maintain the car in position on the cradle. It will be understood that 65 the sheaves F² are in place merely to guide the two counterweight cables around the corner of the cradle, the take-up counterweight travels up with the main holding counterweight but has no influence owing to its light weight in proportion to the holding counterweight. It merely is always present to maintain a tension on the cable system.

It will be noted that the differential action between the large counterweight drum and the small clamp drum gives the counterweight an advantage whereby a relatively light counterweight is sufficient to hold the clamps against the load of the car.

I claim:

1. In a car dumper, a cradle adapted to receive a car, a support for the cradle, clamp holding counterweights mounted in the support, and means for lowering the clamps onto the car through the action of gravity at the beginning of the turning movement of the cradle and means operative only after a predetermined movement of the cradle for connecting the holding counterweights to the clamps.

2. In a car dumper, a cradle adapted to receive a car, a support for the cradle, means for turning the cradle, a movable car clamp, a revolvable drum carried by the cradle having a rope connected to the clamp, and a counterweight mounted in the support for exerting a turning effort on the drum.

3. In a car dumper, a cradle adapted to receive a car and to be turned to dump the car, a support for the cradle, a car clamp carried by the cradle, a drum also carried by the cradle and having holding and lifting ropes connected to the clamp, and a counterweight mounted in the support for exerting a turning effort on the drum.

4. In a car dumper, a cradle adapted to receive a car and to be turned to dump the car, a support for the cradle, a car clamp carried by the cradle, a drum also carried by the cradle and having a rope connection with the

clamp, a counterweight mounted in the support for exerting a turning effort on the drum, and means for connecting and disconnecting the counterweight and drum.

5. In a car dumper, a cradle adapted to receive a car and to be turned to dump the car, a support for the cradle, a car clamp carried by the cradle, a drum also carried by the cradle and having holding and lifting ropes

10. connected to the clamp, a counterweight mounted in the support, and mechanism for causing the counterweight to exert a turning effort on the drum when the cradle has been turned a predetermined amount.

15. 6. In a car dumper, a cradle adapted to receive a car and to be turned to dump the car, a support for the cradle, a car clamp carried by the cradle, a drum also carried by the cradle and having holding and lifting ropes

20. connected to the clamp, a counterweight for exerting a turning effort on the drum, and mechanism by which during a portion of the turning movement of the cradle from and to normal position the counterweight is caused

25. to exert a turning effort on the drum, the counterweight being mounted in the support.

7. In a car dumper, a cradle adapted to receive a car and to be turned to dump the same, a support for the cradle, car clamps carried by the cradle, holding and lifting ropes connected to the clamps, and counterweights mounted in the support for exerting a pull on the holding ropes.

8. In a car dumper, a cradle adapted to receive a car and to be turned to dump the same, a support for the cradle, car clamps carried by the cradle, drums carried by the cradle and provided with holding and lifting ropes connected to the clamps and adapted when turned in one direction to wind in the holding ropes and when turned in the opposite direction to wind in the lifting ropes, and a counterweight mounted in the support for rotating the drum.

45. 9. In a car dumper, a cradle adapted to receive a car and to be turned to dump the same, a support for the cradle, car clamps carried by the cradle, drums carried by the cradle and provided with holding and lifting

50. ropes connected to the clamps and adapted when turned in one direction to wind in the holding ropes and when turned in the opposite direction to wind in the lifting ropes, and a counterweight mounted in the support for rotating the drum, and means for automatically connecting and disconnecting the counterweight and the drums responsive to the rotation of the cradle.

10. In a car dumper, a cradle adapted to receive a car and to be turned to dump the same, a support for the cradle, car clamps carried by the cradle, drums carried by the cradle and provided with holding and lifting ropes connected to the clamps and adapted when turned in one direction to wind in

the holding ropes and when turned in the opposite direction to wind in the lifting ropes, and counterweights mounted in the support adapted to exert a turning force on the drums.

11. A car dumper comprising a rotatable cradle, a car holding clamp thereon, a clamp drum rotatably mounted on the cradle, clamp raising and lowering cables wound thereabout, a counterweight drum mounted for rotation independent of the clamp drum, a holding counterweight removed from the cradle, a cable leading therefrom and wound about the counterweight drum and automatic means for locking the drums together 70 toward the end of the cradle excursion adjacent the dumping position.

12. A car dumper comprising a rotatable cradle, a car holding clamp thereon, a clamp drum rotatably mounted on the cradle, clamp raising and lowering cables wound thereabout, a counterweight drum mounted for rotation independent of the clamp drum, a holding counterweight removed from the cradle, a cable leading therefrom and wound about the counterweight drum and automatic 85 means for locking the drums together toward the end of the cradle excursion adjacent the dumping position, the automatic means including a clutch mechanism interposed between the drums and a cam adapted to hold the clutch mechanism in inoperative position during the movement of the clamp toward and from a car.

13. A car dumper comprising a rotatable cradle, a car holding clamp thereon, a clamp drum rotatably mounted on the cradle, clamp raising and lowering cables wound thereabout, a counterweight drum mounted for rotation independent of the clamp drum, a holding counterweight removed from the cradle, a cable leading therefrom and wound about the counterweight drum and automatic 100 means for locking the drums together toward the end of the cradle excursion adjacent the dumping position, and means for rotating the counterweight drum during rotation of the cradle to take up the slack in the counterweight cable.

14. A car dumper comprising a rotatable cradle, a car holding clamp thereon, a clamp drum rotatably mounted on the cradle, clamp raising and lowering cables wound thereabout, a counterweight drum mounted for rotation independent of the clamp drum, a holding counterweight removed from the cradle, a cable leading therefrom and wound about the counterweight drum and automatic 115 means for locking the drums together toward the end of the cradle excursion adjacent the dumping position, and means for rotating the counterweight drum during rotation of the cradle to take up the slack in the counterweight cable, said means comprising a recessed counterweight and a cable leading 120

125

130

- therefrom and wound about the counterweight drum in a direction opposite to the counterweight cable.
15. A car dumper comprising a rotatable cradle, a car holding clamp thereon, a clamp drum rotatably mounted on the cradle, clamp raising and lowering cables wound thereabout, a counterweight drum associated with the clamp drum of greater diameter, a counterweight removed from the cradle and a cable leading therefrom and wound about the counterweight drum.
16. A car dumper comprising a rotatable cradle, a car holding clamp thereon, a clamp drum rotatably mounted on the cradle, clamp raising and lowering cables wound thereabout, a counterweight drum associated with the clamp drum of greater diameter, a counterweight removed from the cradle and a cable leading therefrom and wound about the counterweight drum, and means associated with both drums for rotating them to take up the slack in the counterweight cable and to raise and lower the clamps.
25. 17. A car dumper comprising a rotatable cradle, a car holding clamp thereon, a clamp drum rotatably mounted on the cradle, clamp raising and lowering cables wound thereabout, a counterweight drum associated with the clamp drum of greater diameter, a counterweight removed from the cradle and a cable leading therefrom and wound about the counterweight drum, and means associated with both drums for rotating them to take up the slack in the counterweight cable and to raise and lower the clamps, said means including a reset carriage mounted for arcuate movement about the periphery of the cradle, a stop limiting the movement of the carriage and cables and sheaves interposed between the carriage and cradle and associated with the drums.
45. 18. A car dumper comprising a rotatable cradle, a car holding clamp thereon, a clamp drum rotatably mounted on the cradle, clamp raising and lowering cables wound thereabout, a counterweight drum mounted for rotation independent of the clamp drum, a holding counterweight removed from the cradle, a cable leading therefrom and wound about the counterweight drum and automatic means for locking the drums together toward the end of the cradle excursion adjacent the dumping position, a ratchet on one of the drums, a pawl on the other, yielding means tending to force them into engagement, a cam tending to hold them out of engagement and means for rotating the drums to disengage the pawl and cam and lock the drums together after the clamps are seated on a car.
55. 19. A car dumper comprising a rotatable cradle, a car holding clamp thereon, a clamp drum rotatably mounted on the cradle, clamp raising and lowering cables wound thereabout, a counterweight drum mounted for rotation independent of the clamp drum, a holding counterweight removed from the cradle, a cable leading therefrom and wound about the counterweight drum and automatic means for locking the drums together toward the end of the cradle excursion adjacent the dumping position, a ratchet on one of the drums, a pawl on the other, yielding means tending to force them into engagement, a cam tending to hold them out of engagement and means for rotating the drums to disengage the pawl and cam and lock the drums together after the clamps are seated on a car.
65. 20. In a car dumper, a rotatable car holding cradle, a clamp thereon movable toward and from the car, a clamp holding rope and a clamp lifting rope, means interposed between the cradle and its support for operating the lifting rope, to raise the clamp away from the car as the cradle rotates into the upright position, a counterweight removed from the cradle adapted to exert a holding tension on the cable and to hold the clamps when the car is in the dumping position only, and a take-up counterweight adapted to exert a tension on the cables to maintain them taut during rotation of the cradle.
21. In a car dumper, a cradle adapted to receive a car and to be turned to dump the same, a support for the cradle, car clamps carried by the cradle, drums carried by the cradle and provided with holding and lifting ropes connected to the clamps and adapted when turned in the opposite direction to wind in the lifting ropes, and a clamp lifting counterweight and a clamp holding counterweight adapted to exert turning force on the drums.
- Signed at Chicago, county of Cook and State of Illinois, this 13th day of December 1927.
- WILLARD E. ERICKSON.
